UNITED STATES PATENT OFFICE.

LAWRENCE TURNER FAIRBANK, OF CAMBRIDGE, MASSACHUSETTS.

RETOUR FOR THE DISTILLATION OF OIL SHALES.

Application filed April 23, 1926. Serial No. 104,189.

This invention relates to a retort for the distillation of oil shales for the production of shale oil, but may be also applied to the distillation of coal, lignite or for other similar substances.

An object of the invention is the provision of a retort which may be revolved and uniformly heated for the uniform heating of the shale within the retort and which is adapted to be operated under a low pressure of a vacuum and at low temperatures whereby cracking is reduced and the time of distillation is diminished.

A further object of the invention is the provision of a retort which will produce a rapid distillation of the oil shale and also yield a greater quantity of shale oil than is ordinarily produced in the exhausting tubes of retorts, provision being made for the injection of steam towards the end of the distillation to insure a greater formation of gas from the nearly spent shale and for the recovery of nitrogenous products, especially the ammonium compounds.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a longitudinal view of a retort constructed in accordance with the principles of my invention, with part of the shell broken away.

Figure 2 is an end view.

Figure 3 is a transverse vertical section taken along the line 3-3 of Figure 1.

Referring more particularly to the drawings, 10 and 11 designate a pair of spaced standards, with standard 10 having a specially constructed bearing 12 at its upper end, with standard 11 having a bearing 13 for the purpose of receiving a trunnion 14 connected to a rear end wall 15 of the cylindrical retort 16. This retort is formed of sections made of steel drums with flanges 17 for connecting the adjacent ends of the drums together.

The end wall 15 is provided with a lower internal bearing 18 to receive one end

of a conduit 19 having a plurality of openings 20^a in direct communication with the interior of the retort.

The opposite end of the retort, as shown at 21, has a stuffing box 22 through which passes an end of the conduit 19 and is supported by the bearing 12.

The bearing 13 has a threaded nipple 23 to which is connected by means of a union 24 a pipe 25 forming an inlet for steam. A sleeve 18^a is in open communication with the pipe 25 through the bearing 13 and the bearing 18. The pipe 19 is closed, as shown at 19^a. Suitable means is provided for injecting steam when required into the body of the retort at a point near the end wall 15. Steam from pipe 25 enters the hollow bearing 18 and sleeve 18^a and is discharged through the radially disposed pipes 20 which are in open communication with the sleeve 18^a. As the steam escapes from the free ends of the pipes it sweeps the oil vapors from the retort and through the perforations 20^a which are located in the conduit 19 and thence to the condensers which will be presently described. The pipe 19 beyond the end 21 of the retort passes through the bearing 22 and is connected to a discharge pipe 26 for the gases and vapors from the retort, the pipe 26 being in turn connected with a condensing system.

A suitable source of steam is connected with pipe 25 for supplying steam under low pressure near the end of the distillation of the oil shale and is delivered to the retort through the open ends of the pipes 20. A valve 28 in the pipe 25 is adapted to control the admission of steam while the valve 27 in the pipe 26 is adapted to not only control the escape of the vapors from the retort 16 but adapted to control the pressure within the retort whether this pressure is a negative pressure due to a vacuum, or a pressure higher than atmosphere due to the low pressure steam.

The retort 16 is not only supported by the trunnion 14 and bearing 13, the outer end of pipe 19 and cooperating bearing 12, but also by means of rings 29 and 30 secured to the intermediate portions of the retort 16 and between the flanges 17 of the sections of the retort which rest upon grooved rollers 31 carried by shafts 32 which in turn are mounted in bearings 33 at the upper ends of bearing blocks 34. These blocks may be formed of metal or

some composition material such as concrete. It will be appreciated that a pair of these rollers are located in spaced relation beneath the retort and transversely of the retort for properly supporting the intermediate portions of the retort, as shown in Figure 1. The extreme ends 15 and 21 are provided with a ring gear as shown at 35 which are maintained in engagement with gears 36 driven synchronously from shafts 37. These shafts extend to any suitable rotating element. These shafts are provided with bearings 38 and 39 formed in the standards 10 and 11.

15 An opening 40 is shown at one end of the retort for filling the retort with materials or for discharging the spent materials from the same. A cover plate 41 which has its inner surface ground to neatly fit the adjacent surface of the retort is bolted to the retort to prevent the loss of fluid during operation. The standard 11 has a metal box 42 which has a covered opening 43 with which is adapted to align the opening 40 of the retort so that the materials are discharged directly through the opening of the box 42.

The operation of my device is as follows:

30 The shale is admitted through the opening 40 in the retort and when a sufficient quantity has been supplied the cover 41 is bolted in position and the shafts 37 are revolved whereby the retort will be revolved and the speed of revolution is predetermined and maintained substantially constant. In order to create a vacuum in the retort 16 a vacuum pump may be connected with the pipe 26 with the valve 28 closed and the gas is turned on to the burners 44 located below 40 the retort. It will be appreciated that the retort may be heated in any suitable manner as by means of grates or an electric heating resistance secured to the outer surface of the retort and which is placed in communication with a source of current by a revolving contact.

50 The pressure is kept reduced in the retort during the distillation of the oil shales and during the total time of heating except when steam is admitted so that cracking is reduced and the time of distillation is likewise reduced. By such a process the quantity of material handled within a definite time will be greatly increased. The vacuum 55 is continuous from the retort to the condensers. The construction of the retort provides for a uniform heating of the shale and

therefore a more uniform and perfect yield of shale oil. The vapors of the shale oil pass through the openings in the conduit 19 60 then through the ends of the pipe into the bearing 12 and through the pipe 26 to condensers, the valve 27 being open while valve 28 is closed. Near the end of the period of distillation steam is admitted with low 65 pressure to complete the distillation of the almost spent shale and for aiding in the recovery of nitrogenous products, particularly the ammonium compound.

From the pipes 20, steam is discharged 70 into the retort and will sweep the oil vapors from said retort.

What I claim is:

1. A retort for the distillation of oil shales comprising a cylindrical member having its 75 ends closed and horizontally positioned, a perforated conduit passing centrally and axially of the cylindrical member, one end of the conduit being closed and the other end passing through an end of the retort 80 and projecting beyond said end of the retort, a conduit passing through the other end of the retort and receiving the closed end of the perforated conduit, a steam pipe connected with the second mentioned conduit, said second mentioned conduit being 85 provided with means to discharge steam into the retort, said last mentioned means including pipes connected with the second mentioned conduit and projecting radially 90 therefrom, the free ends of the conduits being open, and means for rotating the cylindrical member.

2. A retort for the distillation of oil shales comprising a cylindrical member having its ends closed and horizontally positioned, a perforated conduit passing centrally and axially of the cylindrical member, one end of the conduit being closed and the other end passing through an end of the 100 retort and projecting beyond said end of the retort, a conduit passing through the other end of the retort and receiving the closed end of the perforated conduit, a steam pipe connected with the second mentioned conduit, said second mentioned conduit being 105 provided with means to discharge steam into the retort, said last mentioned means including pipes connected with the second mentioned conduit and projecting therefrom, the free ends of the conduits being open, and means for rotating the cylindrical member.

LAWRENCE T. FAIRHALL.
